PAGE 4

Fig. 4

Fig. 5

FIGURE 1 is a plan view of a hard surface floor covering embodying my new design, with a design unit being enclosed within the outermost horizontal and vertical lines which unit is repeated in regular succession as indicated by the extensions beyond the unit boundaries;

FIGURE 2 is an enlarged view of the upper left quarter of the portion delineated by the dash-dot lines of FIG. 1;

FIGURE 3 is an enlarged view of the upper right quarter of the portion delineated by the dash-dot lines of FIG. 1;

FIGURE 4 is an enlarged view of the lower left quarter of the portion delineated by the dash-dot lines of FIG. 1; and

FIGURE 5 is an enlarged view of the lower right quarter of the portion delineated by the dash-dot lines of FIG. 1.

I claim:

The ornamental design for a hard surface floor covering or similar article, substantially as shown and described.
